METAL AWNING

Filed June 12, 1929

UNITED STATES PATENT OFFICE

AMOS E. STENZEL, OF WHITTIER, CALIFORNIA, ASSIGNOR OF ONE-FOURTH TO PAUL G. RITTER, ONE-FOURTH TO CHARLES R. WELSH, BOTH OF LOS ANGELES, CALIFORNIA, AND ONE-FOURTH TO JULIAN A. RACHAL, OF BAKERSFIELD, CALIFORNIA

METAL AWNING

Application filed June 12, 1929. Serial No. 370,287.

This invention relates to awnings comprising strips of sheet metal hinged together and raised and lowered by a running cord; and it includes the novel construction and arrangement of the sheet metal strips, and their combination with each other and with the running cord.

An object of this invention is to provide a simple construction, arrangement and combination of parts for forming an imperforate sheet metal awning of the character stated that is adapted, when raised by the cord, to fold in minimum space compactly against the window frame or other support to which the awning is connected and that is constructed and arranged to be returned by gravity directly when the cord is loosened, but to be held securely erect with only slight tension on the cord.

20 A feature of the invention is that the hinged strips are constructed of different widths so arranged that when the awning is up, its hinges will be at different heights and will not interfere with each other to increase 25 the projection of the folded device, from the face of the support.

An object is to provide a cheap, light, easily built, easily assembled and easily installed attractive metal awning for doors, windows, porches, garden houses and tent frames and for such other structures and uses as may be found desirable.

Further objects are strength, stability, noiselessness anti-rattling construction, and 25 tight connection with the face of the building to prevent water from flowing down between the awning and such face.

A feature of the invention is the provision of horizontal strips of sheet metal having flat 40 return-folds to stiffen and strengthen the body of the awning canopy and to protect against leaking at the canopy joints.

An advantage is the adaptability to manufacture by light and simple machinery.

45 In this invention I am able to provide for great strength of awning made of thin and consequently easily bent sheet steel or other sheet metal, and I have provided at each of the hinge joints between successive strips, a 50 direct return bend and a flat return fold or

ply, terminating in hinge eyes space apart to receive between them, hinge eyes of the meeting edge of an adjacent strip, and a pintle uniting the eyes and assisting in strengthening the joint and making it practically inflexible except around the pintle for folding and for extension.

55 A further feature of the invention is the provision, at the canopy ends of running connections for the flexible cord for folding the awning, so that there will be no unsightly 60 obtrusion on the view, of means for adjusting the awning.

In this respect the hinge pintles are extended beyond the ends of the hinges and are bent 65 into eyes through which the cord may be run, or in which rings may be linked to receive such cords.

70 Other objects, advantages and features of invention may appear from the accompanying drawings, the subjoined detailed description and the appended claims.

The accompanying drawings illustrate the invention.

75 Figure 1 is a perspective view of an awning constructed in accordance with this invention, and mounted in place on a building and lowered for the protection of a window; a portion of which, with a fragment of the building is shown.

80 Fig. 2 is an elevation of a specimen of the awning folded up.

Fig. 3 is an edge elevation of the awning shown in Fig. 2.

85 Fig. 4 is a fragmental section of the lower part of the awning when lowered as shown in Fig. 1.

90 Fig. 5 is a fragmental detail of the construction at one end of the cross bar of the awning as shown in Fig. 1, such cross bar of the frame being in section.

Fig. 6 is an enlarged fragmental elevational detail of an awning mounted in place on a window frame and folded.

Fig. 7 is an elevation in section on line $\alpha\beta$, Fig. 6, looking in the direction of the arrows.

Fig. 8 is a section at the upper joint when the awning is lowered.

Fig. 9 is a fragmental section analogous to Fig. 8, showing two of the hinge joints.

Fig. 10 is an edge view of the joint with pulley ring and loop at the end opposite to that shown at the upper part of Fig. 9.

The rings for forming the running connection between the awning hinge joints and the awning cord, are shown raised to avoid confusion of lines.

The awning canopy as shown, comprises a series of thin sheet metal pieces as at 1, 2, 3, 10 4, 5, forming head, foot and intermediate strips, provided with flat return-folds or laps 6, 7, 8, 9, 10 and 11. For the larger awnings, the return-fold members forming the laps may be held together by spot-welding, as at *a* in Fig. 9, or by rivets as at *a'* in Fig. 4; but in the narrower awnings such welding and riveting is found to be ordinarily unnecessary for such places.

I have found that in the construction shown; galvanized sheet metal of 28 gage affords ample strength, and that such slight thickness of metal is desirable on account of its lightness and the ease with which it may be bent tight and flat upon itself.

25 The uppermost lap 6 of the head section 1 is arranged to lie flat against the face of the window frame 12 or other part of a building onto which the awning is applied, and is secured thereto by suitable means as wood screws 13; and is made water-tight by a coating of white lead paste 14. Each of the laps 7, 8, 9, 10 and 11 is provided at its edge with an eye *b* for the pintles, as at 15, 16 and 17; and in some instances the pintles may, 35 and in others may not be provided at their ends with eyes as at 18, 19.

The awning cord 20 is shown rove through pulley blocks 21, 21', supported by hooks 22 fixed to the building; and the ends of the 40 cord may be run through loops 18 formed by bending the projecting ends of the pintles 16, and may be fixed to the eyes 19 of the foot pindle 17.

Preferably after the pintles 16 are run 45 through the hinge eyes, and before the projecting ends are bent, they are run through pulley rings 23 and are then bent into loops so the rings are linked therewith and serve as pulleys through which the ends of the 50 cord are passed on their way to the loops 19, to which such ends are fixed.

The cord 20 may be thin wire cable, or may be connections of any appropriate flexible character.

55 In the drawings only one intermediate pindle is shown provided with a ring, but it is understood that the number of pintles employed depends on the number of strips, and each of such pintles may be provided at each 60 end with the pulley or running ring; ordinarily such rings are provided for every other joint of the canopy.

The frame at the bottom of the lowered awning is of a well known construction comprising the two side arms 24 and the cross

arm 25 which may be of gas pipe connected together by a T pipe fitting 26 into which the side arms 24 and 25 are screwed; and ornamental tips 27 are shown screwed into the T pipe-fitting to give a finished appearance to the frame.

The side arms are provided with hinge fittings 28 that are pivoted to brackets 29 on the building.

The head section 1 has a longitudinal obtuse bend as at 30 so that its flat upper and lower wings terminating in the return folds 6 and 7 are in angular relation to each other; and the angle is such that when the upper wing as at 6 is flat against the upright wall 80 12, the lower wing as at 7 will have an outward and downward slope practically corresponding to the pitch of the lowered screen, as indicated by the broken lines in Fig. 7; and the lower fold 7 may be wide enough 85 to project beyond sections of the awning to discharge the drip clear beyond such sections.

The foot section 2 is shown journalled to the cross-bar 25 by loops 31 of sheet metal 90 which may be fixed to the foot section by any suitable means as by rivets as at *a'* in Figs. 4 and 7, or by spot welding, as may be preferred.

In practical manufacture the strips with 95 their eyes may all be made by machinery, not shown in the drawings, and may then be appropriately joined edge to edge and secured by the pintles, the appropriate ones of which will be provided at one end with an eye and a ring held thereby, and will be of a length greater than the width of the awning; and after the pintles are run through the hinge eyes they are to unite, the protruding ends may be inserted through rings and 100 then bent into loops to hold the rings.

It is understood however that if the rings are not available, the cord may be passed directly through the loops; but such arrangement is not shown in the drawings, and the 110 form shown is preferred because the cord runs more smoothly.

It is seen from the foregoing that the awning may be made by hand or by machinery in modes of operation well understood by those skilled in the art of working with sheet metal; the strips being appropriately notched at opposite edges in off-set manner as is common in leaf hinges, so that the hinge forming tongues of one edge of a strip will fit in the notches of the meeting edge of an adjacent strip, and so on.

To raise the awning the cord will be drawn down in the usual way and wound around the keeper 32.

To lower the screen the operation is reversed.

The drape 33 may be of any desired pattern and is hinged to the foot section 2 by the lower pindle 17.

The strips may be ornamented in any desired manner as by the striping shown, and this may be applied by painting, enameling or otherwise, either before or after the strips are hinged together by the pintles.

5 I claim:—

1. An awning comprising a sheet metal head strip, a sheet metal foot strip and intermediate strips hinged together by pintles extending from end to end of the awning; the head strip having flat return-bends and folds forming laps at their upper and lower edges; said head strip having an intermediate obtuse longitudinal bend so that said strip is formed of two wings arranged in angular relation to each other parallel to the intermediate bend of said strip; said folds being on the convex side of the strip so that when the upper fold is fastened against an upright support the seams will be at the convex side 10 of the head strip, and the hinge for the lower fold will be accommodated between the lower fold and the upright support, and one or more succeeding hinges below will extend under cover of said lower fold; the terminals of 15 one or more of the pintles projecting beyond the edges of the strips and bent to form loops for the purpose of making connection with a running cord for raising and lowering the 20 awning.

2. In an awning comprising sheet metal strips having hinge eyes at their edges; a pindle to pivot the eyes together; said pindle extending beyond the ends of the strips and being provided with loops for connection with the running cord for raising the awning.

3. In an awning composed of sheet metal strips, a head strip provided with upper and lower return-bends and folds, and longitudinally bent between said folds from end to end so that when the top fold is fastened against a vertical support, the lower fold will extend outwardly from said support; the edge of the under fold being hinged to a lower strip and provision being thus made for accommodating such hinge in the space between the lower fold and such support.

4. An awning comprising a series of parallel sheet metal strips provided with hinge loops at their edges; pintles hinging said loops together; one of the strip edges at each hinge being formed with a flat lap return bend, the upper edge of which forms a pindle eye.

5. The combination with sheet metal strips hinged together, of means for fastening an upper strip to a support; a frame adapted to be hinged to such a support and to a lower strip; a pulley swung to the support; a cord 50 connected to the lower hinge and having a running connection with an intermediate hinge and bent through the pulley and depending therefrom to be operated by hand; and means hinging the lower strip to a cross-bar of the frame.

6. An awning comprising strips of sheet metal hinged together at their edges and of different widths, and arranged so that when the awning is folded, the hinge portions will be at different levels.

7. An awning comprising strips of sheet metal hinged together at their edges and of different widths so that when the awning is folded up, the hinge portions will be at different levels; the head strip being longitudinally bent obliquely so that its upper and lower wings will be in angular relation to each other; the upper wing being adapted to be fixed against an upright in the plane of the upper limb and the lower hinges being 75 so in front of such plane.

In testimony whereof, I have hereunto set my hand at Los Angeles, California, this 6th day of June, 1929.

AMOS E. STENZEL.
